H. CLAYTON SIMMONS,

BY *Franklin Scott*, ATTORNEY.

UNITED STATES PATENT OFFICE.

HORATIO CLAYTON SIMMONS, OF NORTH BENNINGTON, VERMONT.

STEAM HEATING APPARATUS.

SPECIFICATION forming part of Letters Patent No. 513,369, dated January 23, 1894.

Application filed January 26, 1893. Serial No. 459,873. (No model.)

To all whom it may concern:

Be it known that I, HORATIO CLAYTON SIMMONS, of the village of North Bennington, in the county of Bennington and State of Vermont, have made certain new and useful Improvements in Furnaces and in Methods of Using the Same, of which invention the subjoined description, in connection with the accompanying drawings, constitutes a specification.

The invention relates especially to that class of heaters designed to warm dwellings and other buildings by the diffusion of steam through pipes and radiators from a stationary boiler. It lies partly in special construction of the apparatus employed, and partly in the peculiar method of firing and using such specially constructed apparatus. It has among other things for its object to maintain a low but uniform degree of boiler pressure throughout the system, to consume a minimum of fuel, to secure perfect combustion and the maximum consumption of smoke and gases and to minimize the duties of the attendant.

The leading characteristics of the apparatus for carrying out my invention are: First, an abnormally deep but relatively narrow fire box whereby a large body of coal is kept in a compact, columnar mass during the process of combustion, the top of the column reaching to the under side of the boiler. Second. A grate composed of independently rotatable bars closely set and finely indented so as to retain without sifting through a considerable body of ashes upon their upper surface. These ashes as hereinafter explained play an important part in the operation of the furnace. Third. Provisions for draft automatically regulated so as to supply the fire with only as much air as will promote slow and uniform combustion throughout the whole column of ignited coal, whereby the combustible gases are evolved slowly and only as fast as they can be ignited and consumed in their passage through the flue circulation. Fourth. In use the grate is never raked or cleared of ashes. When the ash accumulation on the grate bed has attained a depth demanding relief, only a portion of such accumulation is discharged and this is done by giving one or more of the bars as the case may require a half or whole turn, thus sweeping out off the bottom of the

furnace only the ashes lying within reach of the revolving bar; the superincumbent mass above that point simply settles down and takes the place of the discharged ashes; but this is not carried to the extent of breaking into the burning mass of live coals in the middle of the fire box.

The successful operation of this boiler and furnace depends upon keeping at all times a bed of ashes under the live coals through which the direct draft must find its way and in its passage through which it becomes heated so as to practically constitute a hot blast.

The invention is fully disclosed in the drawings wherein in Figure 1 I have shown a semi-elevation of one end of the heater and also a semi-transverse vertical section of the boiler and its setting taken on the line 1—2 of Fig. 2. Fig. 2 is a vertical longitudinal section of the heater taken just in front of the axis of the boiler. Fig. 3 is a horizontal plan showing the top of the boiler, back damper, position of the feed door, &c. Fig. 4 shows a plan of the fire grate.

The apparatus consists of the horizontal boiler B which relatively is quite short, provided with a number of sets of tubular flues (three in this case,) b, b' and b'', set in brick in the usual way. It is provided with a flue chamber at one end which is divided, by the partition k located between the upper and middle sets of tubes, into two divisions I and K. This chamber is closed by a flue door Q, by opening which access to the flues is obtained for purposes of cleaning them. In use this door is securely and tightly closed. A flue space is left at the opposite end of the boiler which is divided between the middle and lower sets of tubes by the slide damper plate E and between the upper set of tubes and the top of the boiler is the plate l. Thus the chambers J and H are constituted, between which communication is had through the aperture e, which may be closed by slide G operated by the handle g. Access to chamber J is obtained through door O and passage P for removing deposits accumulating thereon from cleaning flues b' and b''. The fire box and ash pit beneath it are of quite limited horizontal area relatively, but of excessive depth. The purpose of which is to burn the coal in column rather than in a shallow

or thin stratum, spread over the surface of an open grate.

The walls of the fire box are so constructed that the coal can be filled in close up to the 5 under side of the boiler and so as to touch the same if desired, and in use the fire box is kept practically so charged.

The grates C C are placed far enough below the boiler to allow a considerable depth of 10 ashes as at f'' to accumulate thereon equivalent to from one sixth to one third of the vertical space between the top of the grate and the under side of the boiler. The direct draft to support combustion passes through 15 the opening S and is controlled by the damper s' which is connected by a rod or chain with an automatic regulating steam diaphragm attached to the boiler, whereby the admission of air to the fire is automatically regulated. 20 The grate consists of a number of bars C C which are mounted in the frame C' C'' and are adapted to be revolved independently of each other. The frame in which they rest consists of a bar of iron C' which is bent to 25 the form shown in Fig. 4 its front ends being bolted to the cross bar C⁴. The upper edge of this bar is fitted with bearings in which the bars rest and turn. They are held, confined in place by the cap bar C'' which is similarly bolted to the bar C'. This mode of construction permits the cap bar to be taken off so that the bars may be removed or changed. These bars are set closely together and are so 30 toothed as to prevent the free sifting of ashes 35 through them, except when they are turned. Their outer ends are squared for the reception of a crank or handle by which they may be turned independently of each other. Each of them is provided with a locking dog d 40 which consists simply of a small piece of metal bent at right angles and pivoted to the cap bar C''. To turn the bar this dog is turned up which leaves the bar free to be revolved. Provisions of some sort for this purpose are necessary 45 to prevent the rotation of the bars adjacent to the one under manipulation and thereby disturbing the whole bed of the fire, when perhaps it is necessary to agitate only a limited part of it. These provisions for limited 50 agitation of the bed of the fire as well as to localize the area of such agitation are essential to the complete and perfect operation of the apparatus. With a proper charge of ashes reposing on them each may be successively 55 and independently rotated without breaking up the bed of the fire so as to let the live coal down within the reach or influence of the fresh draft. A semi-revolution of a grate bar 60 will only cause the discharge of the ashes lying in its immediate vicinity.

A small perforated pipe Y leads from the external air through the wall of the furnace and bridges one end of the fire box as shown in Figs. 1 and 2, through which fine jets of air 65 to promote the combustion of gas and smoke can find access to the surface of the burning coal beneath the boiler.

The feed door of the fire box R is set at as high an elevation above the grate as is practicable and opposite the side of the boiler instead of being located beneath the end of the 70 same.

Special advantages in connection with the above described features of construction accrue from the altitude and lateral position of 75 the feed door. The door being placed abreast the center of the fire box as indicated by the dotted lines in Fig. 2, the fresh coal can be deposited evenly over the bed and the box can be filled up to the bottom of the boiler 80 throughout its entire length as shown.

The top of the brick setting of the boiler is carried up high enough to leave a clear space I between it and the upper side of the boiler from which space communication is 85 made to the chimney, and this space is protected with a covering of refractory or non-radiating material to retain heat. In this case I have shown as a cover an iron cap in the form of pan or tray filled with sand. 90 Through this pass the steam pipes U U which connect with the manifolds V V. From these, independent pipes W W connect with each radiator so that each may be independently controlled. Water for the boiler is supplied 95 through the pipe X from any convenient source of supply. The boiler is equipped with the usual fittings, safty-valve, pressure gage, water glass, cocks, &c., which are not shown as they are well understood. 100

The operative principle upon which this apparatus is constructed and worked is as follows: A bed of ashes f'' is either spread over or is allowed to accumulate on the grate of a sufficient depth to effectually restrict and obstruct a free supply of air to the fire from below. This bedding of ashes also serves another and important purpose of preventing the radiation of heat from the fire downwardly to the ash-pit, thus aiding to conserve all the efficiency 110 of the coal. Upon this ash bed the fire is maintained and controlled in the following manner: The fire chamber being prepared and charged as above described and generally with coal enough to last from twelve to twenty-four 115 hours, the diaphragm connections for controlling the damper s' are properly adjusted and so as to admit the least adequate volume of air. When sufficient steam has developed to expel the air from and charge with steam the system of pipes and radiators and produce the proper temperature, the damper s' will close. For this purpose a pressure of from two to ten pounds of steam according to varying 120 conditions under which the apparatus is working, is sufficient. This pressure is obtained when the coal is in a dull red state of ignition, the lowest portion of the fire next to or just above the ash bed as at f' being in the highest state of ignition. As is well known, 125 in the initiatory stages of combustion the gases given off are much richer in carbon than in the last stages, when more hydrogen is developed, and the supply of air to effect

combustion of these gases being admitted at one end of the fire box and at the top of the fuel close to the boiler, the flame thus created must travel the whole length of the boiler 5 and close to it before it passes over the bridge *a* to the chamber *H* and thence to the flues *b*. Thus by this slow process of combustion which is closely analogous to the coking process or the destructive distillation of coal as 10 in the process of gas making, a much higher degree of economy and efficiency in the consumption of the coal is attained than when the bed of the fire is kept clear of the ashes. The combustion is so complete and perfect 15 that everything combustible is burned clean so that the residuum is nothing but a clean ash entirely free from cinders or coke.

As the economy and efficiency of any steam generator depends on holding the temperature 20 under the boiler down as closely as possible to the point which will barely generate sufficient steam to charge the pipes and radiators and compensate for the condensation, it has been found that all coal burning apparatus 25 or furnaces for heating boilers, in which there is no muffling of the under side of the burning coal to retard combustion as herein provided, burn coal wastefully and consequently generate too much steam pressure 30 and a large amount of heat is wasted. Such apparatus cannot be well controlled in mild weather or under moderate temperatures. When only a moderate heat is required, the capacity of the fire box can be regulated as 35 well as the draft by the rotation of a single grate bar or by the rotation of two, one on each side of the center of the furnace as may

be found expedient; or by opening damper *G* the circulation through the tubes *b* and *b'* can be checked and the same sent directly 40 from the fire chamber to the upper set of tubes *b''* and thence through flue *L* to the chimney.

I therefore claim as my invention—

1. The combination with a horizontal tubular boiler, of the described close fire box of columnar proportions, having its feed door located abreast the approximate longitudinal center of one side of the boiler and above the plane of the under side of the same, and having 50 a grated bottom composed of independently rotatable grate bars of fine mesh, and a draft aperture beneath said fire box, substantially in the manner described and for the purposes specified. 55

2. In combination with a horizontal steam boiler, an incasement or setting fitted with a feed door horizontally and laterally opposite the lower half of the boiler, a passage way for fuel leading downwardly therefrom to the bottom of the fire box and opening inwardly to the under side of the boiler so that fuel may be supplied to the fire and banked up in close contact with the under side of the boiler, substantially in the manner described and for 60 the purposes specified. 65

In testimony whereof I have hereto subscribed my name, at the village of North Bennington, Vermont, this 31st day of December, A. D. 1892.

H. CLAYTON SIMMONS.

In presence of—

EMILY SCOTT,
FRANKLIN SCOTT.
